SPARKING PLUG

Gustav Ruthardt, Stuttgart, Germany

Application April 14, 1938, Serial No. 201,968

3 Claims. (Cl. 123—169)

This invention relates to a sparking plug for internal combustion engines for different kinds of fuel, in which the sparking plug housing is extended beyond the central electrode and forms a sparking chamber with a conically narrowing outflow passage and several sub-compartments of alternately increasing and decreasing cross-sectional area, the mass-electrode being arranged within the combustion chamber.

According to the invention the insulating body is mounted in a separate sleeve removably inserted in the sparking plug body and secured thereon by a clamping nut. In the lower part of the sleeve the mass-electrodes are arranged which are connected with the central electrode fixed in the insulating body. The insulating body with inserted central electrode in conjunction with the sleeve and the mass-electrodes forms a separate insertion which is placed in the sparking plug body after being adjusted. The insertion with sleeve in which the insulating body is fixed with the central electrode is removably inserted in the known sparking plug body and fixed by a screw cap. The central electrode has a collar below the end of the insulating body, which collar affords a particularly effective protection against the known objectionable cracking of the lower point of the insulating body. Thus, by means of the closed insertion, the mass-electrodes can be accurately adjusted to the central electrode before being inserted in the sparking plug body. In sparking plugs with fore-chamber it was very difficult if not impossible to effect a precise mutual adjustment of the electrodes. By means of the separate insertion and the fixation of the insulating body in the sleeve, the latter can be accurately set with care and attention, with the result that one-sided pressures on the insulating body are prevented, this having not been possible in the known constructions in which it sometimes happens that, when inserting the insulating body in the sparking plug body, a one-sided pressure is exerted on the insulating body which chips easily and leads to cracking under the explosion pressure and the great heat.

An embodiment of the invention is illustrated by way of example in the accompanying drawing, in which—

Fig. 1 shows the plug in vertical section.

Fig. 2 is a side elevation.

Fig. 3 is a vertical section through the insertion.

Fig. 4 is a bottom plan view of Fig. 3.

Fig. 5 is a top plan view of Fig. 3.

Fig. 6 is a side elevation of Fig. 3.

55 An insulating body *b* is inserted in a sleeve *a*

and fixed by a clamping nut *c*. For obtaining tight joints in the sleeve a packing ring *d* is placed in the nut *c* and a packing ring *e* in the sleeve *a*. The ring *f* is fixed in the lower part of the sleeve *a* in known manner, for example by bending over. The ring *f* is connected with the mass-electrodes *g* which can be very accurately set relatively to the central electrode *h*. The central electrode *h* has at the lower end of the insulating body *b* a collar *i* which protects the pointed end of the insulating body *b* against chipping. The central electrode *h* has no screw thread at its lower end, whereas its upper end has only a screw threaded extension for the nut for connecting up the cable. The whole insertion *a, b, c, f* and *h* is placed into the sparking plug housing *k* with the electrodes set and is fixed therein by a screw cap *l*. Thus, it is possible to introduce the sparking plug insertion into the sparking chamber *m* with the electrodes accurately adjusted, with the result that any subsequent adjustment of the mass-electrodes *g* to the central electrode *h* is avoided. By unscrewing the cap *l* the insertion *a, b, c* can be removed directly from the sparking plug housing *k*. The sparking plug housing *k* has an extension with combustion chamber of alternately increasing and decreasing cross-sectional area or with a central bore *o* with helical groove *p*. Straight grooves may be provided in the central bore *o* instead of the helical groove *p*.

I claim:

1. Sparking plug for internal combustion engines, comprising a sparking plug housing having at one end a compartment, an insulating body 35 having a central bore, a central electrode in said bore and projecting slightly from the lower end of said body, a sleeve carrying said insulating body and projecting beyond the said projecting end of said central electrode, mass-electrodes 40 fixed in the lower end of said sleeve and distributed around the periphery of said projecting end of said central electrode adjustably clamping said insulating body in said sleeve to determine the relative position of said central electrode 45 and said mass-electrodes, a sparking plug housing having at its upper end a compartment adapted to accommodate said sleeve after the adjustment of said electrodes, a cap securing said sleeve in said compartment, and a screw-threaded extension 50 at the lower end of said housing having a central bore communicating with said compartment.

2. In a sparking plug as specified in claim 1, a collar on the projecting lower end of the central 55

5 electrode at a distance from the extremity thereof, said collar bearing against the lower end of the insulating body and forming a shield above the sparking gap between central electrode and mass-electrodes for protecting the insulating body against cracking.

3. A sparking plug as specified in claim 1, in

which the compartment in the sparking plug housing has a tapered portion at its lower end below the lower edge of the sleeve, said tapered portion forming the sparking chamber, in which the bore in the extension tapers towards this 5 sparking chamber and has grooves in its wall.

GUSTAV RUTHARDT.
